UNITED STATES PATENT OFFICE.

JAMES J. HENNESSY, OF NEW YORK, N. Y.

CONSTANT-LEVEL LUBRICATOR.

Application filed June 21, 1924. Serial No. 721,413.

My invention relates to railroad rolling stock and consists in an improved lubricating device for car or locomotive journals.

In such journals, it is customary to distribute lubricant over the journal face by means of capillary attraction produced by packing the journal with cotton waste and supplying lubricant to the waste. The waste is sometimes saturated with lubricant at intervals and devices have been proposed for pumping lubricant to the waste from a reservoir located below the same and for supplying lubricant from a reservoir above the journal. Each of these methods are open to objections, the first requiring repacking and re-oiling at intervals and the journal and bearing are damaged if this is neglected. The second method involves expensive working parts not always reliable. The third method, so far as I am aware, usually produces an over-supply of lubricant, resulting in waste of the same, or, if a supply valve is utilized, calls for manual operation of the same at intervals, which operation may be neglected.

The object of my present invention is to provide a lubricant reservoir adapted to feed lubricant by gravity to the cotton waste, but equipped with automatic means for maintaining the lubricant at a constant level which will avoid loss of surplus lubricant and at the same time keep the waste saturated to the desired degree.

In the accompanying drawings which illustrate my invention—

Figure 1 is a transverse section through an axle journal and a box applied thereto and containing my invention.

Figure 2 is a vertical transverse section on line 2—2 of Figure 1.

Figure 3 is a longitudinal section through a driver box equipped with a modified form of my invention and illustrating the journal in part.

Figure 4 is a fragmentary section similar to Figure 1 but showing the valve operating parts in valve opening position.

In the construction shown in Figures 1 and 2, the journal is indicated at A and the box at B. The latter has a portion partially enclosing the journal A and adapted to receive a waste container or pan 1, the bottom of which is perforated, yieldingly supported on a partition 2 of the box B by a coil spring 3. The container 1 may be packed with cotton

waste 4 in the usual manner which will always be pressed against the journal by means of the container support. The container preferably has no sides, permitting any surplus lubricant fed to the journal to return freely to the bottom of the container receiving portion of the box. The lower portion 5 of the box constitutes a cellar for lubricant. A reservoir 6, provided with a removable lid 6^a, is carried by the box at one side of the journal and may consist in a sheet metal structure having an opening in its lower wall aligned with a corresponding opening in the upwardly facing wall 7 of the box. The opening in box wall 7 is threaded to receive a plug 8 screwed therein and a nut 9 screwed onto plug 8 serves to clamp the reservoir tightly to the box wall. Suitable gaskets 10 and 11 may be provided between nut 9 and the reservoir bottom and between the latter and the top of the box wall 7.

The plug 8 is provided with a screen S and has a passage the wall of which is shaped to form a valve seat 12, and a valve 13 is positioned in said passage and normally held against its seat by a lever 14 pivoted at 15 on legs 8^a extending downwardly from the plug 8. The longer arm of the lever 14 is supported by a float 16 floating in the oil in cellar 5, the normal oil level being indicated by the dot and dash line C. The float 16 may be of any buoyant material or may be a hollow vessel of sheet metal or the like.

A bolt 17, inserted through the lower wall of the cellar and secured in position by a nut 18, passes through lever 14 and float 16 and serves to position these members.

When the oil level falls below the point in which it affords sufficient buoyancy to the float to hold valve 13 against its seat, the weight of the lever 14 will raise the valve and permit oil to flow from the reservoir through plug 8 into the cellar. The float and lever rising with the oil level closes the valve thus limiting the amount of oil in the cellar.

It is desirable to prevent the opening and closing of the valve by slight variation in the height of the float. Such valve operation is prevented by the pin and slot connection between the lever and valve and by use of a spring 19 compressed between a projection 14^a on lever 14 and a pin 20 carried by plug legs 8^a.

A rod 22 is pivoted to projection 14^a and extends through pin 20. The upper end of the

rod is threaded for nuts 21 and by means of these nuts the force of spring 19 may be adjusted.

When the axis of the spring passes to the left of pivot 15, the spring urges the valve closed. When a substantial portion of the weight of the lever rests on spring 19, the axis of the latter shifts to the right of pivot 15 and opens the valve. (See Fig. 4.) Generally the slapping of the oil in the cellar will be insufficient to operate the valve.

When the valve is open, a limited rise of the oil will not raise the lever. The rise must be enough to provide sufficient buoyancy to overcome spring 19 and shift its axis to the left of post 15.

The spring compression may be so adjusted by nuts 21 that the shifting takes place upon any desired movement of the float and different conditions of box construction, journal diameter, or other working conditions accommodated.

In the construction shown in Figure 3, the box D corresponds to box B in having a partition wall 23 which separates the cellar 24 from the portion which receives the distributor plate 25. A reservoir 26 is mounted upon an elevated portion 27 of the box and is secured thereto by a plug 28 which is screwed into the top wall of the box and is provided with an annular flange 29 engaging the lower wall of the reservoir. Suitable gaskets 30 and 31 are provided between the flange 29 and the reservoir bottom and between the latter and the wall of the box.

Plug 28 has a downwardly facing valve seat and the valve 32 is seated thereon by the float 33 attached directly to the valve by means of washers 34 and cotters 35. The valve 32 has a stem 36 extending upwardly through plug 28 and provided with a pin 37 which prevents the valve from dropping away from the plug in the event that the supply of lubricant in the reservoir and cellar should be exhausted.

The float 33 may be inserted in the cellar through opening 38 and may be positioned through a drain opening normally closed by a plug 39.

In either of the devices shown, it is only necessary to supply lubricant to the reservoir at intervals quite lengthy compared with the proper intervals for packing the ordinary box; and if this is done the lubricant will be supplied to the lower portion of the waste in sufficient amount to properly lubricate the journal. The supply of lubricant will be controlled automatically and in the preferred form illustrated this control may be varied by simple adjustment of nuts 21. It will be noted that vertical adjustment of plug 8 will vary the height of pivot 15, thereby affording means for controlling the oil level irrespective of the use of spring 19 and nuts 21.

The details of my invention may be modi-

fied without departing from the spirit of my invention as expressed in the appended claims.

I claim:

1. In a journal lubricator, a lubricant reservoir, a lubricant distributor, a lubricant cellar below said reservoir and distributor and connected to each by passages and carrying said reservoir, a valve for the passage between said reservoir and cellar, a pivoted lever operatively engaging said valve, a float supported by lubricant in said cellar and operatively engaging said lever, a spring for limiting the functioning of said float, and adjustable means for controlling said spring. 70 75 80

2. In a journal lubricator, a cellar, a lubricant distributing member, a lubricant reservoir above said cellar, a threaded opening in the wall of said cellar, a plug screwed into said opening and provided with a valve seat and with a leg projecting into said cellar, a valve seated therein and extending into said cellar, a lever pivoted on said leg and operatively engaging said valve, a float in said cellar operatively engaging said lever, and a spring mounted on said lever and leg to yieldingly hold said lever in valve closing position. 85 90 95

3. In a journal lubricator, a cellar, a lubricant distributing member, a lubricant reservoir above said cellar, a threaded opening in the wall of said cellar, a plug screwed into said opening and provided with a valve seat and with a leg projecting into said cellar, a valve seated therein and extending into said 100 cellar, a lever pivoted on said leg and operatively engaging said valve, a float in said cellar operatively engaging said lever, and a spring, provided with an adjustable tensioning device, mounted on said lever and leg to yieldingly hold said lever in valve closing position. 105

4. In a journal lubricator, a cellar, a lubricant distributing member, a lubricant reservoir above said cellar, a threaded opening in the wall of said cellar, a plug screwed into said opening and provided with a valve seat and with a leg projecting into said cellar, a valve seated therein and extending into said cellar, a lever pivoted on said leg and operatively engaging said valve, a float in said cellar operatively engaging said lever, and adjustable means cooperating with said float to hold said lever in valve closing position. 110 115

5. In a journal lubricator, a cellar, a lubricant distributing member, a lubricant reservoir above said cellar, a threaded opening in the wall of said cellar, a plug screwed into said opening and adapted to be secured at different heights therein and provided with a valve seat and with a leg projecting into said cellar, a valve seated therein and extending into said cellar, a lever pivoted on said leg and operatively engaging said valve, a float in said cellar operatively engaging said 120 125 130

lever, and means mounted on said leg for yieldingly holding said lever in position.

6. In a journal lubricator, a cellar, a lubricant distributing member, a lubricant reservoir above said cellar, a threaded opening in the wall of said cellar, a plug screwed into said opening and adapted to be secured at different heights therein and provided with a valve seat and with a leg projecting into said cellar, a valve seated therein and extending into said cellar, a lever pivoted on said leg and operatively engaging said valve, a float in said cellar operatively engaging said lever, and adjustable means cooperating with said float to hold said lever in valve closing or opening position.

7. In a journal lubricator, a lubricant cellar, a lubricant reservoir attached to said cellar, aligned openings in the contacting walls of said cellar and reservoir, an apertured exteriorly threaded element in said cellar projecting through the opening in the wall of said reservoir, and a nut inside said reservoir fitting said element and adapted to be screwed thereon to clamp the wall of said reservoir to the wall of said cellar.

8. In a railroad journal lubricator, a lubricant reservoir, a lubricant receiving cellar connected therewith, a valve controlling the passage of lubricant from said reservoir to said cellar, a float in said cellar, a valve operating element controlled by said float, and means providing for limited movement of said float before said element operates said valve.

9. In a journal lubricator, a lubricant reservoir, a lubricant receiving cellar connected therewith, a valve controlling the passage of lubricant from said reservoir to said cellar, a valve operating lever, yielding means adapted to urge said lever to valve closing or valve opening position, and a float for controlling the functioning of said lever and means.

45 10. In a journal lubricator, a cellar, a lubricant distributing member, a lubricant reservoir above said cellar, a threaded opening in the wall of said cellar, a plug screwed into

said opening and provided with a valve seat and with a leg projecting into said cellar, a valve seated therein and extending into said cellar, a lever pivoted on said leg and operatively engaging said valve, a float in said cellar operatively engaging said lever, and a spring mounted on said lever and leg to yieldingly hold said lever in valve closing or opening position.

11. In a railway journal lubricator, a journal box, a waste containing distributing member therein, a supply reservoir, a device, including a float, for automatically maintaining in said member a constant level of lubricant from said reservoir, and means for adjusting the height of said device relative to said reservoir to vary the lubricant level maintained in said reservoir.

12. In a journal lubricator, a lubricant reservoir, a lubricant cellar for supplying lubricant to the journal to be lubricated, a lubricant passage from said reservoir to said cellar, a valve in said passage, a float in said cellar, a connection between said float and valve to open and close the latter as the level of lubricant in said cellar falls and rises respectively, said connection including a device providing for lost motion of said float to prevent operation of said valve from open to closed position or vice-versa until there has been a predetermined movement of said float.

13. In a lubricator of the class described, a lubricant reservoir, a lubricant cellar, a passage between said reservoir and cellar, a valve for said passage, a lever for operating said valve, a pivot for said lever, an angular shoulder on said lever adjacent to said pivot, an element pressing against said shoulder so that its line of thrust extends approximately through the angle of said shoulder and may be shifted to opposite sides of said pivot to yieldingly hold the lever in either of two positions relative to said valve.

In testimony whereof I hereunto affix my signature this 27th day of May, 1924.

JAMES J. HENNESSY.
